SAFETY MECHANISM FOR FIREARMS

William C. Roemer, New Haven, and Clifford R. Lines, Hamden, Conn., assignors to Olin Industries, Inc., New Haven, Conn., a corporation of Delaware

Application December 31, 1946, Serial No. 719,578

13 Claims. (Cl. 42—70)

1

The present invention relates in general to firearms and more particularly to safety-mechanisms for firearms to prevent inadvertent discharge of the latter.

An object of the invention is to provide an improved safety-mechanism for firearms wherein the safety-mechanism is operated automatically to lock the firing-mechanism each time the action is closed.

A further object of the invention is to provide a superior action-operated safety-mechanism for firearms.

A further object is to provide a bolt-action firearm with a superior safety-mechanism which automatically locks the trigger as the bolt is being moved into breech-closing position, and manually-operated means cooperatively associated with the safety-mechanism to move the latter out of engagement with the trigger so as to permit manipulation of the trigger after the bolt is locked in breech-closing position.

A still further object of the invention is to provide a superior bolt-operated automatic safety-mechanism for firearms which, when moved into operative position by the bolt, will remain therein until manually released; and manually-operated means cooperatively associated with the safety-mechanism to indicate the "safe" and "firing" positions respectively of the latter and to render it inoperative so as to permit the firearm to be fired after the bolt is locked in breech-closing position.

A still further object of the invention is to provide a firearm with a superior action-operated automatic safety-mechanism which is characterized by its elementary structure and its simplicity and economy of manufacture.

With the above and other objects in view, as will appear to those skilled in the art from the present disclosure, this invention includes all features in the said disclosure which are novel over the prior art.

In the accompanying drawings, in which certain modes of carrying out the present invention are shown for illustrative purposes:

Fig. 1 is a broken view in side elevation and partly in section of an upturn-and-pullback bolt-action firearm in which the present invention is incorporated, the stock and associated parts being omitted and the safety-mechanism being shown in its "firing" position;

Fig. 2 is a sectional end elevation on line 2—2 of Fig. 1;

Fig. 3 is a sectional end elevation on line 3—3 of Fig. 1;

2

Fig. 4 is similar to Fig. 1 but shows the positions which the elements of the safety-mechanism assume as the breech-bolt is moving into breech-closing position;

5 Fig. 5 is a view corresponding to Fig. 4 but showing the positions which the elements of the safety-mechanism assume when the bolt is locked in breech-closing position;

10 Fig. 6 is a bottom view of the breech-bolt partly in section and showing the relative positions of the safety-operating cam-slot in the sleeve-element of the breech-bolt and an element of the safety-mechanism when the sleeve has been rotated into the breech-bolt-locking position of Fig. 1;

15 Fig. 7 is a fragmentary view of the breech-bolt shown in Fig. 6 but with the sleeve-element of the breech-bolt in its unlocked position of Fig. 4, the cam-slot of the sleeve being shown out of engagement with the element of the safety-mechanism;

20 Fig. 8 is a perspective view of the breech-bolt sleeve showing the safety-operating cam-slot therein;

25 Fig. 9 is a perspective view of the sear-and-trigger unit including the sear-notch which is formed as an integral part of the trigger;

Fig. 10 is a perspective view of the novel safety-slide of this invention; and

30 Fig. 11 is a perspective view of the finger-piece for manually operating the slide of the safety-mechanism.

The safety-mechanism of the present invention is suitable for use in connection with various 35 firearm structures but the particular firearm herein chosen for illustration is of the so-called "upturn-and-pullback" bolt-action type. The said firearm includes a receiver 20 of tubular form into the forward end of which the rear end 40 of a barrel 21 is threaded. The receiver 20 is also provided with an axial bolt-receiving passage 22, the forward upper portion of which is intersected by a loading-and-ejection opening 23.

45 Mounted in the bolt-receiving passage 22 of the receiver 20 with capacity for reciprocation therein is a cylindrical bolt 24. The cylindrical bolt 24 is of conventional construction and is described more fully in Patent No. 2,174,971 Crockett, October 3, 1939. Briefly, however, the bolt comprises a firing-plunger 25, the forward end of which is adapted to project through an eccentric firing-point aperture in the face of the bolt. The firing-plunger is spring-pressed forwardly in the bolt by the force of a coil-spring 50 26 which is mounted in a concentric axial bore

27 in the rear end of the bolt, the rear end of the coil-spring 26 being retained therein by a plug 28 secured in the rear extremity of the bore 27 by a transverse pin 29. The forward end of the spring 26 is arranged to engage the shoulder 30 of a cocking-projection 31 which extends downwardly from the underside of the firing-plunger. The firing-plunger 25 is also formed on its underside and forwardly of the cocking-projection 31 with a second projection 32 having a forwardly-facing sear-shoulder 33 which is adapted to be engaged by a rearwardly-facing shoulder 34 of a sear-notch 35 formed upon the forwardly-extending substantially-horizontal reach 36 of the sear-and-trigger unit of the firing-mechanism generally designated by the reference character 37. Rearwardly of the projection 32, the bolt 24 is reduced in diameter to provide a cylindrical shoulder 90 and a cylindrical bearing-surface 38 for a breech-bolt operating-sleeve 39 which is rotatably mounted on the reduced rear-end portion 38 of the bolt and held from moving longitudinally thereon by the aforesaid shoulder 90 and a retaining-sleeve 40, the latter being secured to the reduced rear end of the bolt by the aforesaid transverse pin 29. The breech-bolt operating-sleeve 39 is provided adjacent its forward end with a laterally-projecting operating-handle 41 which terminates in a ball-grip 42; and at its rear end with a cam-slot 43 which intersects the rear edge of the sleeve and is adapted to cooperatively engage the cocking-projection 31 of the spring-pressed firing-element to cock the latter in the usual manner by the upturn movement of the operating-handle 41. The forward edge of the cylindrical bolt-operating sleeve 39 presents a substantially-square shoulder 44 which is intersected by a substantially-triangular-shaped safety-operating cam-slot 45. The leg 46 of the triangular cam-slot is substantially straight, whereas, the hypotenuse 47 of the triangular cam-slot is slightly arcuate and its cam-surface 48 slopes upwardly and outwardly, as indicated clearly in Fig. 7.

Referring to Fig. 9, the sear-and-trigger unit 37 embodies, in addition to the sear-shoulder 34 of the sear-notch 35, a cartridge-ejector blade 49 formed at the forward extremity of the reach 36. The rear end of the sear-and-trigger unit comprises a substantially-horizontal safety-slide supporting-ledge 50 having a trigger-release notch 51 at its rearmost extremity. Formed substantially intermediate the opposite ends of the supporting-ledge 50 is an aperture 52 drilled or otherwise formed in the ledge and projecting downwardly substantially vertically into that portion of the sear-and-trigger unit which corresponds to the finger-piece or trigger per se 53. The aperture 52 is adapted to accommodate a sear-trigger spring 54 and plunger 55; the upper end of the latter being resiliently held by the spring 54 above the surface of the supporting-ledge 50, as indicated in Figs. 1, 4 and 5. Projecting upwardly from the forward end of the supporting-ledge 50 and formed as an integral part of the sear-trigger unit is a tongue 56 which is provided with a transverse aperture 57 adapted to receive a pin 58 for pivotally mounting the sear-trigger unit in the receiver 20, as indicated in Figs. 1 and 2. Provided in the tongue-portion 56 of the trigger-sear unit 37 is a second transverse aperture 59 which is spaced below and somewhat forwardly of the pivot-pin aperture 57 and in which is secured a limit-pin 60, one

5 end of which is flush with its respective face of the sear-trigger unit, the opposite end projecting laterally beyond its corresponding face of the trigger-sear unit, as shown clearly in Figs. 2 and 3, and for the purpose hereinafter described.

Referring to Fig. 10, the principal element of the automatic safety-mechanism of this invention is indicated generally at 61 in Fig. 10 and comprises a sheet-metal slide consisting of a U-shaped saddle-portion 62 having spaced parallel side walls 63 and 64 and a top wall 65. Formed integrally with and extending rearwardly from the rear edge of the top wall 65 of the saddle-portion is an elbow 66 having a substantially-vertical depending trigger-locking arm 67 terminating in a substantially-square edge 68. The wall 63 of the saddle 62 has an integral forwardly-extending panel 69 which is provided with a substantially-rectangular slot 70 intersecting its upper edge. The opposite wall 64 of the saddle is provided with an integral forwardly-extending reach 71. The reach 71 comprises an upwardly-projecting leg-portion 72 having a nose-portion 73 at its upper extremity which projects upwardly at substantially right angles to the longitudinal axis of the slide and has spaced parallel edges 76, the upper rear corner of the nose 73 being provided with a relief-notch indicated generally by the reference character 74 and comprising a substantially-horizontal flat 75 terminating at its rear end in the substantially-vertical rear wall or shoulder 77 of the nose 73, the lower end of the rear wall 77 being blended by a substantially-90° radius into the substantially-horizontal upper edge 78 of the leg 72. The upper edge 78 of the leg 72 is provided with a substantially-rectangular clearance-slot 79 which is forwardly of and considerably larger than the slot 70 in the opposite wall 63 of the saddle. As shown clearly in Fig. 10, the clearance-slot 79 comprises substantially-vertical front and rear edges 80 and 81 respectively and a bottom edge 82, for the purposes hereinafter described.

Referring to Figs. 1, 4 and 5, the slide 61 of the automatic safety-mechanism is adapted to be mounted on the slide-supporting ledge 50 of the sear-trigger unit 37 and to this end, the saddle 62 of the safety-slide is engaged over the ledge 50 with the opposite walls 63 and 64 of the saddle engaging on opposite sides respectively of the sear-trigger unit. It will be noted, however, that the underside of the top wall 65 of the saddle does not slidably engage the ledge 50 of the sear-trigger unit but is held above the ledge 50 in vertically-spaced relationship thereto by engagement of the upper end of the spring-mounted plunger 55 with the underside of the top wall 65 of the saddle. Further, as assembled on the sear-trigger unit, the laterally-projecting end of its transverse pin 60 is adapted to engage in the rectangular clearance-slot 79 of the reach 71 of the safety-slide. The latter is thus enabled to move forwardly and rearwardly with respect to the sear-trigger unit, its longitudinal movement in either direction being limited by engagement of the projecting end of the pin 60 with the vertical edges 80 and 81 respectively of the slot 79. Moreover, 65 it will be noted that when the safety-slide is mounted on the sear-trigger unit the elbow 66 of the slide is resiliently held in engagement with the underside of the receiver and constitutes, in effect, a fulcrum about which the slide may engage 70 limited pivotal movement. More particularly,

the nose 73 at the forward end of the slide, is free to swing downwardly. It will be noted however, that in the normal position of the slide, the lower edge 82 of the slot 79 of its reach 71 is resiliently held in engagement with the projecting end of the transverse pin 60 by the force of the spring-loaded plunger 55 acting on the safety-slide 61 forwardly of its fulcrum-elbow 66, as a consequence of which the slide has no pivotal movement upwardly or in a counterclockwise direction from its position, as seen in Figs. 1, 4 and 5.

Referring to Figs. 2, 3 and 11, the safety-slide 61 of the safety-mechanism is adapted to be cooperatively associated with the manually-operated finger-piece 83 which is provided at one end with a knurled finger-engaging lip 84 and at its opposite end with a substantially-rectangular key 85. Intermediate the opposite ends of the finger-piece 83 is an aperture 86 adapted to receive a screw 87 which is threadedly engaged in an aperture in the receiver wall and by which the finger-piece 83 is pivotally secured to the outer wall of the receiver. As assembled on the receiver, the finger-engaging lip 84 is uppermost and the key 85 is adapted to extend downwardly and inwardly into engagement with the rectangular slot 70 of the safety-slide. Thus, by swinging the finger-piece forwardly and rearwardly manually, the safety-slide 61 may be moved both rearwardly and forwardly respectively. Conversely, longitudinal movement of the slide rearwardly and forwardly respectively will impart pivotal movement to the finger-piece 83, the finger-engaging lip 84 of which is associated with suitable indices such as, for instance, the letters S and F engraved or otherwise formed in the adjacent wall of the receiver, to indicate the "safe" and "firing" positions respectively of the safety-slide 61.

The operation of the improved safety-mechanism may be described briefly as follows:

In Fig. 1 the breech-bolt 24 is shown in breech-closing position, in which position it has been locked by turning down the operating-handle 41. The firing-element 25 has been cocked and is held in cocked position by engagement of the sear-shoulder 33 of the firing-element with the shoulder 34 of the sear-notch 35 in the sear-trigger unit. It will be clear that the force of the sear-trigger spring 54 acting on the plunger 55 to thrust the latter upwardly into engagement with the saddle of the safety-slide 61 rearwardly of the sear-trigger unit pivot-pin 58, tends to hold the forward end or reach of the sear-trigger unit upwardly, whereby the respective shoulders 33 and 34 of the firing-element and sear-trigger unit are resiliently held in mutual engagement, the latter being capable, however, of disengagement by pulling the trigger 53 rearwardly to displace the sear-shoulder 34 of the trigger. Moreover, the thrust of the plunger 55 acting on the safety-slide 61 forwardly of its fulcrum-elbow 66 tends to urge the forward end or nose 73 of the safety-slide upwardly into cooperative engagement with the cam-slot 45 of the bolt-operating sleeve 39, the fulcrum 66 of the trigger-locking arm 67 being held in engagement with the underside of the receiver-unit. However, in Fig. 1, the safety-slide 61 has been moved into a position such that the sear-trigger unit 37 is free to be pivoted downwardly about its pivot 58 to disengage the respective sear-engaging surfaces of the firing-element and sear-notch. To this end, the finger-piece 83 of the safety-mechanism has been

swung forwardly or clockwise manually, thereby moving the safety-slide 61 rearwardly and positioning the lower edge 68 of the trigger-locking arm 67 opposite the trigger-release notch 51 in the rear extremity of the ledge 50, whereby the trigger 53 is unlocked and may be pulled rearwardly, as indicated by the broken lines in Fig. 1, to release the firing-element 25.

After the trigger has been pulled and the cartridge fired, the firearm is reloaded in the customary manner by grasping the ball-terminal 42 of the operating-handle 41 and pulling it upwardly and rearwardly. Referring again to Fig. 1, when the breech-bolt 24 was locked in breech-closing position, the nose 73 of the safety-slide 61 was engaged in the triangular cam-slot 45 of the operating-sleeve 39. Consequently, when the operating-sleeve is rotated to cock the firing-element and withdraw the breech-bolt from breech-closing position, the adjacent edge 76 of the nose 73 is engaged and displaced downwardly by the sloping cam-surface 48 of the cam-slot 45, which action pivots the safety-slide 61 downwardly clockwise about its fulcrum-elbow 66 against the resistance of the spring-mounted plunger 55, the upper edge of the nose 73 riding on the periphery of the forward end of the rotating operating-sleeve. On retracting the bolt, the periphery of the bolt-operating sleeve rides off of the nose 73 of the safety-slide, whereupon the spring-mounted plunger snaps the nose of the safety-slide back up into its normal position. It will be noted, however, that the safety-slide 61 has not been displaced longitudinally from its firing position of Fig. 1.

Assuming the bolt has been fully retracted by the bolt-operating handle and the fired cartridge ejected by engagement with the ejector-blade 49 of the sear-trigger unit, a new cartridge may be loaded into the chamber of the barrel. As the bolt is advanced toward chamber-closing position, the shoulder 77 of the safety-slide 61 is engaged, first, by a bolt radius 88 which may be described as that cylindrical surface of revolution which blends the flat 89 on the bottom of the bolt 24 with the flat 900 of a cylindrical bolt-shoulder 90 formed at the forward end of the reduced rear end 38 of the bolt, whereby the nose 73 of the safety-slide is again cammed downwardly slightly against the resistance provided by the spring-pressed plunger 55 as the bolt moves forwardly. As a consequence of this action, the flat 900 of the cylindrical shoulder 90 of the bolt moves into the relief-notch 74 of the safety-slide nose 73, with the flat 75 of the latter in engagement with the flat 900 of the cylindrical bolt-shoulder 90.

Referring to Figs. 4 and 5, as the bolt 24 continues forwardly into chamber-closing position, the forward edge 44 of the operating-sleeve will be brought into engagement with the substantially-vertical shoulder 77 of the nose 73 of the safety-slide, whereupon the bolt picks up the safety-slide and moves it forwardly positively with respect to the sear-trigger unit, which longitudinal movement is permitted by the spacing of the vertical walls 80 and 81 of the clearance-slot 79 of the safety-slide. With the initial forward movement of the safety-slide 61, the finger-piece 83, the key 85 of which is engaged in the slot 70 of the safety-slide, will be pivoted counterclockwise from its former firing position to a position which is initially substantially intermediate its "firing" and "safe" positions, as clearly shown in

Fig. 4. However, to insure safety, the position of the safety-slide 61 with respect to the sear-trigger unit at the time the finger-piece 83 is intermediate its "firing" and "safe" positions, is such that the lower end 68 of the trigger-locking arm 67 is actually in engagement with the rear extremity of the ledge 50 of the sear-trigger unit, whereby the trigger is locked, so as to prevent inadvertent release thereof before the bolt is fully locked in breech-closing position. It will be noted that with the respective elements of the bolt, safety-slide and sear-trigger unit in the relative positions shown in Fig. 4, the projecting end of the transverse limit-pin 60 is substantially intermediate the opposite edges 80 and 81 respectively of the clearance-slot 79 of the safety-slide.

On completion of the breech-bolt locking operation, the additional forward movement of the bolt operating-sleeve 39 serves to move the slide 61 to its extreme forward position, in which position the pin 60 is in engagement, substantially, with the rear edge 81 of the clearance-slot 79, as shown clearly in Fig. 5. Moreover, the finger-piece 83 has been pivoted counterclockwise to its extreme rearward position, thereby uncovering the index mark "S" on the receiver, so as to indicate that the safety is "on." It will be noted, moreover, that the final forward movement of the safety-slide has brought the trigger-locking arm 67 forwardly further along the ledge 50, the lower edge 68 of the arm being fully seated thereon, so as to positively lock the trigger; and that the down swing of the operating-handle 41 has rotated the bolt-operating sleeve 39 clockwise and brought the cam-slot 45 thereof substantially opposite the nose 73 of the safety-slide 61. The firearm is now cocked for firing, but before doing so, the gunner must manually engage the lip 84 of the finger-piece 83 and pivot the latter clockwise to a position such as to uncover the index mark "F" on the receiver. In pivoting the finger-piece 83 clockwise, the safety-slide will be pulled rearwardly, thereby moving the trigger-locking arm 67 opposite the trigger-release notch 51 in the rear end of the trigger-ledge 50 and unlocking the trigger. Since the nose 73 of the safety-slide is substantially opposite the cam-slot 45 of the bolt-operating sleeve, the safety-slide may be moved rearwardly, the only resistance to the retraction of the safety-slide being that which is set up by the camming engagement of the upwardly-and-forwardly-inclined wall of its notch 74 with the bolt radius 88, the coaction of which lowers the upper edge of the nose 73 below and into contact with the bolt-flat 900 against the restraining force of the sear-trigger spring 54. The resistance provided by the latter to the downward displacement of the nose 73 of the slide constitutes a detent for the finger-piece 83 whereby the latter is prevented from swinging forwardly and rearwardly freely about its pivot 87. Having swung the finger-piece 83 forwardly so as to snap the nose 73 of the safety-slide into cooperative engagement with the safety-operating cam-slot 45 of the operating-sleeve 39, the bolt-firing mechanism and safety-mechanism are again in the relationship shown in Fig. 1. It will be evident, of course, that until the cam-slot 45 of the bolt-operating sleeve is opposite the nose 73 of the safety-slide, the latter cannot be moved to firing position.

From a consideration of the foregoing description, it will be evident that the improved safety-mechanism of this invention has few parts, all of which are relatively simple to fabricate and

inexpensive to manufacture. Moreover, the safety-mechanism is superior in performance to safety-mechanisms which have heretofore been used and is characterized by its bolt-operated trigger-locking action, whereby the trigger is automatically locked each time the bolt of the firearm is moved into breech-closing position.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

We claim:

1. A firearm including in combination: a reciprocable breech-bolt having a spring-pressed firing-element; bolt-operating means constructed and arranged to load the spring of said firing-element; firing-mechanism arranged to releasably hold said spring-pressed firing-element in spring-loaded position; and safety-mechanism having a forwardly-extending deflectable nose-portion arranged to extend up into the path of said bolt-operating means so as to be actuated by said bolt-operating means as said breech-bolt is moved into breech-closing position, the actuation of said safety-mechanism by said forwardly-moving bolt-operating means serving to engage and lock said firing-mechanism so as to prevent the release of said spring-loaded firing-element.

2. A firearm including in combination: a reciprocable breech-bolt having a spring-pressed firing element; bolt-operating means constructed and arranged to load the spring of said firing-element; firing-mechanism arranged to releasably hold said spring-pressed firing-element in spring-loaded position; safety-mechanism having a forwardly-extending deflectable nose-portion arranged to extend up into the path of said bolt-operating means so as to be actuated by said bolt-operating means as said breech-bolt is moved into breech-closing position, the actuation of said safety-mechanism by said forwardly-moving bolt-operating means serving to engage and lock said firing-mechanism so as to prevent the release of said spring-loaded firing-element; and manually-operable means pivotally secured to said firearm, said means having articulated engagement with said safety-mechanism so as to disengage the latter from locking engagement with said firing-mechanism.

3. A firearm including in combination: a reciprocable breech-bolt having a spring-pressed firing-element provided with a sear-shoulder; bolt-operating means constructed and arranged to load the spring of said firing-element and to move said bolt to and from breech-closing position; firing-mechanism comprising a sear-trigger unit mounted on said firearm and provided with a sear-notch arranged to cooperatively engage the sear-shoulder of said firing-element to releasably hold said spring-pressed firing-element in spring-loaded position; a shoulder on said bolt-operating means; and safety-mechanism comprising a slide mounted on said sear-trigger unit, said slide having a forwardly-extending deflectable nose-portion arranged to extend up into the path of said bolt-operating means so as to be engaged by the shoulder of said bolt-operating means as the latter moves said bolt

into breech-closing position thereby to automatically displace said slide relative to said sear-trigger unit to lock said sear-trigger unit and prevent displacement of said sear-notch from the sear-shoulder of said spring-loaded firing-element.

4. A firearm including in combination: a reciprocable bolt having a spring-pressed firing-element provided with a sear-shoulder; bolt-operating means constructed and arranged to load the spring of said firing-element and to move said bolt to and from breech-closing position; firing-mechanism comprising a sear-trigger unit mounted on said firearm and provided with a sear-notch arranged to cooperatively engage the sear-shoulder of said firing-element to releasably hold said spring-pressed firing-element in spring-loaded position; a shoulder on said bolt-operating means; safety-mechanism comprising a slide mounted on said sear-trigger unit, said slide having a forwardly-extending deflectable nose-portion arranged to extend up into the path of said bolt-operating means so as to be engaged by the shoulder of said bolt-operating means as the latter moves said bolt into breech-closing position thereby to automatically displace said slide relative to said sear-trigger unit to lock said sear-trigger unit and prevent displacement of said sear-notch from the sear-shoulder of said spring-loaded firing-element; and manually-operated means pivotally secured to said firearm, said means having articulated engagement with said slide and arranged to displace said slide in a direction opposite to its direction of displacement by the shoulder of said bolt-operating means so as to unlock said sear-trigger unit.

5. A bolt-action firearm including in combination: a receiver; a barrel connected to said receiver; a reciprocable breech-bolt mounted in said receiver and having a spring-pressed firing-element; breech-bolt operating-means arranged to cock said spring-pressed firing-element and to move said breech-bolt into breech-closing position; firing-mechanism comprising a sear-trigger unit arranged to releasably hold said spring-pressed firing-element in cocked position; and safety-mechanism comprising a slide counted freely between said sear-trigger unit and said receiver, said slide having a forwardly-extending deflectable nose-portion arranged to extend up into the path of said bolt-operating means so as to be moved automatically along said sear-trigger unit by said breech-bolt operating-means as the latter moves said breech-bolt into breech-closing position, the actuation of said safety-mechanism by said forwardly-moving bolt-operating means serving to engage and lock said sear-trigger unit so as to prevent the release of said cocked firing-element.

6. A bolt-action firearm including in combination: a receiver; a barrel connected to said receiver; a reciprocable breech-bolt mounted in said receiver and having a spring-pressed firing-element; breech-bolt operating-means arranged to cock said spring-pressed firing-element and to move said breech-bolt into breech-closing position; firing-mechanism comprising a sear-trigger unit arranged to releasably hold said spring-pressed firing-element in cocked position; safety-mechanism comprising a slide mounted freely between said sear-trigger unit and said receiver for reciprocal movement on said sear-trigger unit, said slide having a fulcrum arranged to engage the underside of said receiver and a forwardly-extending nose-portion arranged to ex-

tend upwardly into the path of said bolt-operating means initially to be pivoted downwardly and subsequently to be moved automatically along said sear-trigger unit by said breech-bolt operating-means as the latter moves said breech-bolt into breech-closing position thereby to engage and lock said sear-trigger unit and prevent the release of said cocked firing-element; and manually-operated means pivotally secured to said receiver, said means having articulated engagement with said slide and arranged to displace said slide in a direction opposite to its direction of displacement by said bolt-operating means so as to unlock said sear-trigger unit.

15 7. A bolt-action firearm including in combination: a receiver; a barrel connected to said receiver; a reciprocable breech-bolt mounted in said receiver and having a spring-pressed firing-element; breech-bolt operating-means arranged to cock said spring-pressed firing-element and to move said breech-bolt into breech-closing position, firing-mechanism comprising a sear-trigger unit arranged to releasably hold said spring-pressed firing-element in cocked position; safety-mechanism comprising a slide mounted freely between said sear-trigger unit and said receiver for reciprocal movement on said sear-trigger unit, said slide having a forwardly-extending deflectable nose-portion arranged to extend up into the path of said bolt-operating means so as to be moved automatically along said sear-trigger unit by said breech-bolt operating-means as the latter moves said breech-bolt into breech-closing position thereby to engage and lock said sear-trigger unit and prevent the release of said cocked firing-element; a limit-pin carried by said sear-trigger unit arranged to cooperatively engage said slide to limit the longitudinal movement thereof relative to said sear-trigger unit; and a manually-operated finger-piece pivotally secured to said receiver, said finger-piece having articulated engagement with said slide and arranged to displace said slide in a direction opposite to its direction of displacement by said bolt-operating means to unlock said sear-trigger unit and to automatically engage the deflectable nose-portion of said slide in locking engagement with said bolt-operating means.

8. In a bolt-action firearm, the combination 50 with a receiver; a barrel connected to said receiver; a reciprocable breech-bolt mounted in said receiver having a spring-pressed firing-element provided with a sear-shoulder; breech-bolt operating-means constructed and arranged to load the spring of said firing-element and to move said breech-bolt to and from breech-closing position; firing-mechanism comprising a sear-trigger unit mounted in said receiver and provided with a sear-notch arranged to cooperatively engage the sear-shoulder of said firing-element to releasably hold said spring-pressed firing-element in spring-loaded position; a shoulder on said bolt-operating means; safety-mechanism comprising a slide mounted on said sear-trigger unit, said slide having a nose-portion arranged to be engaged by the shoulder of said bolt-operating means as the latter moves said bolt into breech-closing position to automatically displace said slide relative to said sear-trigger unit thereby to lock said sear-trigger unit so as to prevent displacement of said sear-notch from the sear-shoulder of said spring-loaded firing-element; resilient means carried by said sear-trigger unit arranged to engage said slide to hold the nose-portion thereof up into the path of movement of

the said shoulder of said bolt-operating means; and manually-operated means pivotally secured to said receiver, said means having articulated engagement with said slide and arranged to displace said slide in a direction opposite to its direction of displacement by the shoulder of said bolt-operating means so as to unlock said sear-trigger unit.

9. A bolt-action firearm including in combination: a receiver; a barrel connected to said receiver; a reciprocable breech-bolt mounted in said receiver and having a firing-element; breech-bolt operating-means arranged to cock said firing-element and to move said breech-bolt into breech-closing position, said operating-means having a shoulder provided with a notch and a handle for locking said breech-bolt operating-means in breech-closing position; firing-mechanism arranged to releasably hold said firing-element in cocked position; a safety-slide having a nose-portion, said nose-portion being arranged initially to be engaged by the shoulder of said breech-bolt operating-means as the latter moves said breech-bolt into breech-closing position to engage and lock said firing-mechanism so as to prevent the release of said cocked firing-element, said nose-portion being arranged subsequently to lie opposite the notch of said breech-bolt operating-means when the latter has been locked in breech-closing position by said operating-handle; and manually-operated means having articulated engagement with said safety-slide to retract the nose-portion of said slide into the notch of said shoulder so as to unlock said sear-trigger unit.

10. A bolt-action firearm, including in combination: a receiver; a barrel connected to said receiver; a reciprocable breech-bolt mounted in said receiver and having a firing-element; breech-bolt operating-means arranged to cock said firing-element and to move said breech-bolt into breech-closing position; firing-mechanism arranged to releasably hold said firing-element in cocked position; a safety-slide constructed and arranged to be actuated automatically by said breech-bolt operating-means to lock said firing-mechanism so as to prevent the release of said firing-element; resilient-means carried by said firing-mechanism and cooperatively associated with said safety-slide normally to hold said firing-mechanism in cooperative engagement with said firing-element, said resilient-means also constituting a detent to control the action of said safety-slide; and manually-operated means having articulated engagement with said safety-slide and adapted to overcome the resistance of said safety-slide detent to unlock said firing-mechanism.

11. A bolt-action firearm including in combination: a receiver-unit; a breech-bolt supported in said receiver-unit and having a firing-element; breech-bolt operating-means arranged to cock said firing-element; firing-mechanism including resilient-means arranged to releasably hold the said firing-element of said breech-bolt in cocked position; and safety-mechanism having a firing-mechanism engaging-portion held resiliently against the underside of said receiver-

unit by said resilient-means so as to permit both pivotal and longitudinal sliding movement of said safety-mechanism relative to said receiver-unit, said breech-bolt operating-means being arranged to engage said safety-mechanism to pivot said safety-mechanism downwardly and move it forwardly longitudinally relative to said firing-mechanism thereby to move the firing-mechanism engaging-portion of said safety-mechanism into abutting engagement with said firing-mechanism so as to prevent the release of said cocked firing-element.

12. In a firearm including in combination: a receiver; a spring-pressed firing-element having a sear-shoulder; reciprocable action-means mounted in said receiver and arranged to load the spring of said firing-element; firing-mechanism having a sear-notch arranged to cooperatively engage the sear-shoulder of said firing-element to releasably hold said spring-pressed firing-element in spring-loaded position; and safety-mechanism comprising a longitudinally-movable slide constructed and arranged to be slidably mounted on said firing-mechanism beneath said receiver and to be engaged and moved forwardly into locking engagement with said firing-mechanism by said spring-loading action-means as the latter is moved forwardly into closed position, thereby to prevent disengagement of the sear-notch of said firing-mechanism from the sear-shoulder of said spring-loaded firing-element.

13. In a firearm including in combination: a receiver; a spring-pressed firing-element having a sear-shoulder; reciprocable action-means mounted in said receiver and arranged to load the spring of said firing-element; firing-mechanism having a sear-notch arranged to cooperatively engage the sear-shoulder of said firing-element to releasably hold said spring-pressed firing-element in spring-loaded position; safety-mechanism comprising a longitudinally-movable slide constructed and arranged to be slidably mounted on said firing-mechanism beneath said receiver and to be engaged and moved forwardly into locking engagement with said firing-mechanism by said spring-loading action-means as the latter is moved forwardly into closed position, thereby to prevent disengagement of the sear-notch of said firing-mechanism from the sear-shoulder of said spring-loaded firing-element; and a manually-operated lever pivoted intermediate its ends to said receiver, said manually-operated lever having an articulated connection at one end with said safety-slide for manually moving said slide to and from its firing-mechanism locking position.

WILLIAM C. ROEMER.
